UNITED STATES PATENT OFFICE.

CHARLES D. UPDEGRAFF, OF PORTLAND, OREGON, ASSIGNOR OF ONE-HALF TO JOHN A. BERNARD, OF PORTLAND, OREGON.

LUNCH-CARRIER FOR AUTOMOBILES.

1,240,391.

Specification of Letters Patent. Patented Sept. 18, 1917.

Application filed December 9, 1916. Serial No. 135,977.

To all whom it may concern:

Be it known that I, CHARLES D. UPDEGRAFF, a citizen of the United States, residing at Portland, in the county of Multnomah 5 and State of Oregon, have invented a new and Improved Lunch-Carrier for Automobiles, of which the following is a specification.

My invention has reference to that class 10 of portable and collapsible luncheon carriers and tables that are particularly designed for being mounted upon the automobile, and my said invention primarily has for its object to provide an attachment of the character 15 stated, for automobiles, of a simple and economical construction, that can be conveniently and securely mounted upon the running board of the automobile, in which the parts, though compactly arranged, are 20 adapted for carrying a large assortment of food stuffs and in which the different drawers or compartments may be readily pulled or swung out in convenient relation to the table, which in my construction forms the 25 closure member for the entire box when the parts are at their collapsed or closed position.

Another object of my invention is the provision, in a lunch box or carrier, of a simple 30 and improved means for rigidly supporting the food stuff holding drawers and in such position that convenient access is had to the articles contained in the said drawers.

With other objects in view which will 35 hereinafter appear, my invention is a lunch box or carrier that embodies the peculiar construction and novel arrangement of the parts stated in the following description, specifically pointed out in the appended 40 claims and illustrated in the accompanying drawings, in which:

Figure 1 is a perspective view that illustrates my invention as applied to an automobile.

Fig. 2 is a perspective view of the box or carrier, the table leaf or front cover being shown down, and one of the upper drawers pulled partly out, one of the lower drawers being also shown as swung outwardly.

Fig. 3 is a cross section of the box, the drawers, and the front cover or table member being at the closed position.

Fig. 4 is a vertical section of one of the upper drawers taken practically on the line 44-44 on Fig. 7.

Fig. 5 is a similar view taken on the line 5-5 on Fig. 7, the drawer being shown at the pulled out position.

Fig. 6 is a cross section taken on the line 6-6 on Fig. 7. 60

Fig. 7 is an inverted plan view of a set of drawers, one of the drawers being shown at the closed position, and the other at the extended or open position.

Fig. 8 is a detail cross section on the line 8-8 on Fig. 7. 65

Fig. 9 is a detail view that illustrates one of the slotted guide plates and the link member that coöperates therewith.

Fig. 10 is a detail view of one of the link 70 supporting brackets.

Fig. 11 is a similar view of one of the brackets with which the link member pivotally connects, and

Fig. 12 is a detail sectional view of a portion of the invention. 75

In carrying out my invention, I form the body of the box or carrier in the nature of a casing that consists of the ends 1, a center partition 2 that divides the casing into two 80 compartments, a back wall 3, a top 5, and a bottom 4, the outer edge of which at the opposite ends thereof has recesses to receive plates 6 that are attached thereto by countersunk screws 60, and each of which is provided with a lateral extension 61 having an aperture 62 for receiving screw bolts 63 that secure the entire casing or carrier rigidly upon the automobile body, preferably on the running board, as is clearly shown in 90 Fig. 1.

The casing front includes a solid closure portion 7 at the lower end and a cover 8 that is hingedly connected at the lower end, as at 70, to the upper edge of the solid 95 closure member 7.

9-9 designate toggle links that connect to the cover 8 and with the vertically recessed or grooved front edges 80 of the casing ends 1-1, the connection of the said links with 100 the cover 8 and the casing, being such that when the cover is swung up to the closed position, the links fold up into the grooves 80, as shown.

In each casing compartment is mounted 105 a series of drawers, in the present showing there is a vertical tier of three drawers in each compartment, consisting of two deep upper or slideable drawers 10 and a bottom shallow drawer 11, the latter being hing- 110

edly connected for swinging outwardly in the horizontal plane, as will presently more fully appear.

Each of the upper or deep drawers 10 has grooves 12 in the underface of the bottom thereof, which extend from approximately the center of the ends to approximately the center of the front edge, as is best shown in Figs. 7 and 8, by reference to which it will be seen a slotted guide plate 13 is secured over each groove 12 by countersunk screws 14.

The slot 13^a in the plate 13 extends through one end of the plate and is of less width than the groove 12, and in the slots of the said plates 13 ride the studs 15 whose enlarged ends or heads 15^a travel in the grooves 12.

The studs 15 referred to are formed on one end of the link members 16, the other ends of which are pivotally joined, by rivet connections, to brackets 17—17 secured to the opposite ends of the casing space in which the drawer slides.

18—18 indicate bearing brackets, one of which is secured to each of the opposite ends of the casing and located in advance of the respective brackets 17, and the inwardly extended or horizontal bearings 18^a of the said brackets 18 have their outer end inclined downwardly to facilitate riding the links 16 onto the top of the said bearings 18—18 when the drawer is pulled out, as in Fig. 8, it being understood that when the drawer is pulled out, as shown, the bearings 18 serve as a leverage to relieve the brackets 17—17 to which the links are secured, and furthermore, prevent the drawers from falling when pulled out to their limit.

40 The brackets 18 also act as supports for the drawer after the links move off the said brackets, when pushing the said drawer back to the closed position.

By arranging the drawers in tiers, when the cover 7 is down, as shown in Fig. 2, any one or all of the top drawers 10 may be pulled out and readily sustained at their pulled out position by the link members 16, it being also understood that by swinging out, 50 either of the hinged drawers 11, access may be readily had to the compartments 9 in the bottom of the casing and, since the drawers 11, when swung out, rest on the cover 7, the hinges 11^a for the drawers 11 are relieved 55 of the strain of supporting the said drawers 11, when swung out.

From the foregoing description taken in connection with the drawings, the complete construction, the manner of its application 60 and the advantages of my invention will be readily apparent.

While the detail arrangement of the parts shown and described discloses a perfect construction, it is understood that various modifications and changes in the details of

structure may be made without departing from my invention as expressed in the appended claims.

What I claim is:

1. A luncheon carrier comprising a casing having a compartment in the lower end and a side opening above the said compartment, a hinged drop cover for closing the said side opening, means for sustaining the said drop cover at the horizontal plane of the upper edge of the front side of the said compartment, a drawer located over the aforesaid compartment and which forms a top closure for the said compartment, and means for hinging the said drawer to swing outwardly to rest on the hinged drop cover, whereby to give access to the said compartment. 75

15 2. In a carrier of the character stated, the combination with a casing, a drawer slidably mounted therein, the said drawer having a pair of oppositely disposed diagonally positioned guides on the bottom thereof, a pair of opposite links, each of said links being hinged at the inner end to the adjacent inner end of the casing and having the outer end slidably engaging its respective diagonal guide on the drawer bottom, and brackets projected inwardly from the casing ends that form rests for the drawer when pushed in and rests for the links when 90 the drawer is pulled out.

3. In a carrier of the character stated, the combination with an open front casing, of a drawer slidable in the casing, said drawer having a pair of oppositely disposed diagonal grooves that extend from approximately the center of the drawer front to approximately the center of the drawer ends, a pair of links, the said links being hinged at their inner ends to their respective adjacent ends of the casing, each of the said links having a headed stud for engaging their respective diagonal grooves in the drawer bottom, and means on the drawer bottom for holding the headed studs in the 110 grooves.

4. In a carrier of the character stated, the combination with an open front casing, of a drawer slidable in the casing, said drawer having a pair of oppositely disposed diagonal grooves that extend from approximately the center of the drawer front to approximately the center of the drawer ends, a pair of links, the said links being hinged at their inner ends to their respective adjacent ends of the casing, each of the said links having a headed stud for engaging their respective diagonal grooves in the drawer bottom, and means on the drawer bottom for holding the headed studs in the 115 grooves, and brackets projected inwardly from the casing ends on which the links ride and rest when the drawer is pulled to the opening position. 120

5. In a carrier of the character stated, the 130

combination with an open front casing, of a drawer slideable in the casing, the said drawer having a pair of oppositely disposed diagonal grooves that extend from the ends of the drawer to the front edge, longitudinally slotted plates mounted over the said grooves, the slots in each of the said plates extending through one end thereof and be-

ing of a less width than the grooves in the drawer bottom, a link hinged to each casing 10 end, each of the said links having a headed stud for engaging the groove and the slot at their respective ends of the drawer, and means on the casing for sustaining the drawer when pulled out.

CHARLES D. UPDEGRAFF.
